UNITED STATES PATENT OFFICE

ROSSITER S. SCOTT, OF NEW YORK, N. Y.

GARTER PENDANT

Application filed October 21, 1929, Serial No. 401,123. Renewed December 27, 1932.

This invention relates to garters and more particularly to a garter pendant, which when attached to a garter is adapted to support a sock, the garter, when the pendant is detached, being adapted to support a golf or other stocking. In one aspect the invention is an improvement on the pendant for the garter disclosed in my prior application filed July 7, 1928, Serial No. 291,009, patented August 26, 1930, No. 1,773,872.

One of the principal objects of the invention is to provide a convertible garter pendant which will enable the user to change from socks to golf stockings or the like without requiring separate garters for the two uses. Another object is to provide such a garter pendant of simplified construction which will lend itself to economical manufacture. Other and further objects and advantages will be explained in the following description of an illustrative embodiment of the invention, or will be apparent to those conversant with the art.

In the accompanying drawing:

Fig. 1 is a perspective view of a convertible garter comprising a detachable pendant embodying the present invention, and with the two portions shown disconnected.

Fig. 2 is a side elevation of the detached sock supporting pendant.

Fig. 3 is a rear view of the same.

Fig. 4 is an edge view of the free end of the leg encircling band.

Fig. 5 is a face view of said free end of the leg encircling band with the reinforcing piece detached.

Fig. 6 is an edge view of the same and illustrating more clearly the detachable fastener for said reinforcing piece.

Fig. 7 is a face view of an alternative form of pendant plate, which may replace that shown in Figs. 1-3.

Fig. 8 is an edge view of the plate shown in Fig. 7.

The garter illustrated comprises a relatively wide band 10 of elastic or other fabric, having at one of its ends a pad 11 carrying an outwardly projecting headed stud 12, and having at its other or free end 13 a finishing and reinforcing member 14. Near the

free end of the band 10 is a clasp plate 15 formed with a tapered opening or socket 16 adapted to receive the headed end and engage the shank of the stud 12 so as to hold the ends of the band 10 attached in leg encircling form. The socket 16 may have a narrow portion adapted to snap upon the stud shank. These parts are illustrative of any suitable male and female garter fastening.

The clasp plate 15 is preferably narrower than the fabric band 10, and is provided at its opposite ends with suitable openings through which the band may be threaded, said openings being so proportioned that the material of the fabric band will be gathered in gradually and without forming any unsuitable creases or folds therein. One form of such plate is illustrated in my prior application filed March 31, 1928, Serial No. 266,314, patented February 11, 1930, No. 1,747,088, which may be referred to for further detailed description.

The garter as thus far described is adapted to encircle the leg of a wearer and to support a stocking by surrounding the upper portion thereof. In addition to this function, however, the garter can readily be converted to support a sock, as will now be explained. For this purpose, a sock supporting pendant 17 may be detachably secured to the pad 11, preferably by engagement over the stud 12 before the female member 15 is engaged thereover.

The pendant 17 is shown as comprising a plate 18, which is preferably formed of substantially flat rigid metal, and having at its lower end a clasp loop 19 and at its upper end an attaching loop 20. The attaching loop 20 is preferably of less width than the clasp loop 19, and is formed with an opening 21 which is adapted to be engaged over the headed end of the stud 12 on the pad 11. The upper end 22 of said opening 21 is smaller than the diameter of the head of the stud 12, and is preferably so formed as to provide free pivotal movement of the pendant plate on said stud. The two band ends and the pendant are thus in freely swinging relation. The narrow part of the opening be-

tween 21 and 22 may be such as to snap upon the stud shank, giving secure engagement.

- Intermediate the ends of the pendant plate 18 and between the clasp loop 19 and attaching loop 20 are a pair of transverse slots 23, separated by a relatively narrow bar 24. A fabric strap 25 is threaded through said slots 23, and is supported by said bar 24 in such a manner as to lie behind the clasp loop 19.
- 10 The strap 25 is substantially of the same length as the clasp loop 19 and carries, adjacent its lower end, a rubber covered or other button 26, which is adapted to be engaged within the sock and passed through the large upper end of an opening 27 in the clasp loop, and then slid downwardly into the narrowed lower end 28 of said opening. The upper portion of the sock is thus firmly clasped between the button 26 and the loop 19.
- 20 When the garter is to be used to support a sock, the pendant 17 is first hung upon the headed stud 12, and when in use the upper end or attaching loop 20 of said pendant will be positively held against accidental detachment from the fact that the clasp plate 15 overlies it upon the pad 11.
- 30 The finishing and reinforcing member 14, is adapted to be moved up upon the band when the latter is cut off due to stretching or for other reason. It is shown as formed of leather or other suitable material, and it preferably comprises a pair of opposed flap portions 30 and 31, adapted to overlie the front and rear surfaces of the band 10 adjacent said free end. When these two flap portions 30 and 31 are of separate material they are secured together by stitching 32 which extends around and closes the outer end, as well as the short longitudinal edges of the reinforcement. This member 14 is detachably secured to the fabric band 10 by means of a snap fastener having a stud portion 33 which is carried by the flap portion 30, and a cooperating socket portion 34 which is carried by the other flap portion 31. The end 35 of the stud 33 is preferably pointed, so that it can be caused to pierce the fabric before the two portions of the fastener are pressed together.
- 40 The use of the finishing member 14 on the free end of the band simplifies the construction of the garter as a whole, enhances the appearance of the garter, and it makes possible an adjustment of length and a compensation for permanent elongation of the band after it has been in use for some time. For example the fabric band 10 may become elongated to the extent that the clasp plate 15 will require adjustment upon the band to take up slack. Such adjustment necessarily leaves the free end 13 of the band longer than it was originally, and if the wearer should find it to be too long to suit him, he needs only to remove the member 14, cut off a portion of said free end 13 of the band, and then replace the

member 14, and reattach the fastener members 33 and 34.

The pendant 18 is shown as composed wholly of flat metal or plate material, and preferably an integral piece of metal from end to end, as in Figs. 1, 2 and 3. However, an alternative construction can be used as shown in Figs. 7 and 8. In this alternative construction, the lower loop 19^a and upper loop 20^a are separately formed of metal and connected together by a tubular member 38, which extends through the slots 23^a and around the bars 24^a and thus forms a pivotal connection giving flexing of the pendant substantially at the middle. This enables the pendant to conform more readily to the leg of the wearer, and therefore contributes to the comfort of the device. By plate material it is intended to include not only metal, but any equivalent material having suitable stiffness for the purpose.

From the foregoing it will be evident that an efficient convertible garter has been provided, wherein the parts are capable of economical manufacture. The strap 25 is readily engaged with the pendant 17 through the slots 23, and no stitching is necessary as the looped ends of the strap are connected by the eyelet or clip 25^a. A change from one form of garter to the other can be very easily effected, and yet, in either arrangement the garter holds securely in place.

Since various matters of arrangement, combination and construction and operation may be modified without departing from the principles involved, it is not intended to limit the invention to such matters, except so far as set forth in the appended claims.

What is claimed is:

1. A pendant member detachably engageable with the fastener member of a leg band, the pendant comprising a vertical part composed wholly of plate material and provided at its lower end with a relatively movable cooperating part for attachment to a sock, said vertical part being in the form of an integral plate material piece, with two cross slots near its center, and said relatively movable cooperating part being in the form of a strap passing through such slots and carrying a sock engaging member.

2. A sock-supporting pendant for a garter adapted to be articulated with a leg band, said pendant being composed of flat plate material throughout its length, and being provided at its lower end with a clasp loop and being formed intermediate its ends with a pair of parallel transverse slots, and a flexible strap disposed behind said clasp loop and having portions threaded through said slots, and said flexible strap carrying a button to cooperate with said clasp loop in supporting the sock.

3. A sock-supporting pendant for a garter adapted to be detachably mounted on a leg

band, said pendant being formed of a single piece of flat plate material, and being formed at its lower end with a clasp loop and at its upper end with means for detachably engaging the leg band, said pendant being further characterized by a pair of parallel transverse slots intermediate its ends, and a flexible strap suspended from said slots and extending downwardly behind said clasp loop, the strap being provided adjacent its lower end with a button to cooperate with said clasp loop in supporting the sock.

4. In or for a garter, a sock-supporting pendant formed of a single piece of substan-

tially flat rigid plate material, and comprising at its lower end a clasp loop portion and at its upper end a narrower loop portion for connection directly to a leg-encircling band, and the pendant being further characterized by a pair of parallel transverse slots separated by a narrow bar, and a flexible strap associated with said pendant and disposed behind the clasp loop portion, said strap having supporting portions threaded through said transverse slots, and having at its lower end, a button to cooperate with the clasp loop in supporting a sock.
